CARL HENRIK LIEDBECK, OF GOTTFENBORG, SWEDEN.

SEALING OFF FLUIDS IN BOREHOLES FOR OIL WELLS.

Specification of Letters Patent. Patented Feb. 28, 1922.

1,407,873.

Application filed April 2, 1921. Serial No. 458,100.

To all whom it may concern:

Be it known that I, CARL HENRIK LIEDBECK, engineer, a subject of the King of Sweden, residing at Gottenborg, Sweden, have invented certain new and use Improvements in Sealing Off Fluids in Boreholes for Oil Wells, of which the following is a specification.

This invention relates to the process of placing cement between the casing or casings inserted in oil-wells and the surrounding ground by means of first introducing mud or a mixture of clay or other relatively impervious substance and water or other liquid between the casing and the surrounding ground, and afterwards to introduce cement, hydraulic cement or other hardening substance with corresponding or similar qualities through holes or openings made in the wall of the casing or casings into the space between the casing or casings and the surrounding ground. In this description with the claims all the pipes and tubes, inserted in the borehole in order to prevent the caving in of the ground, are called casings.

It has hitherto been the practice when cementing oil-wells through holes or openings made in the wall of the casing or casings, first to clean the space between the casings, and the surrounding ground also the respective walls of the casing and the ground by flushing clear water through this space and afterwards to introduce cement through these holes or openings made in the wall of the casing or casings into the space between the casing or casings and the surrounding ground. This method has the disadvantage of admitting circulation of liquids or gases from one stratum to another or to the open air by means of the free open space between the casing and the surrounding ground, thereby disturbing the cement at the time of its setting, thus preventing it from becoming a hard mass.

The accompanying drawing illustrates in Fig. 1 the manner in which the process has hitherto been performed and in Figs. 2 and 3 the manner in which the process is performed according to the present invention. In the several figures the same reference numerals indicate the same parts.

Fig. 1 is a schematic vertical section of

a borehole. 1 and 3 are groups of different strata in the ground drilled through, 2 is a water-stratum, 4 and 6 are impervious strata and 5 is an oil-stratum. 7 is a casing inserted into the impervious stratum 4 in order to shut off the water flowing from stratum 2. The borehole has been drilled deeper down into the oil-bearing stratum 5 and the well completed by setting a casing 8 down into this oil-stratum in order to maintain a clear passage for the exploitation of oil from stratum 5. Water instead of oil will, however, be pumped to the surface of the ground, showing that casing 7 has failed to shut off the water from above at stratum 4. In order to shut off this water it has been practised to drill holes 9 through casings 7 and 8 opposite stratum 4 and through these holes to pump clear water in order to clean the outer wall of the casing 7 and the wall of the borehole and afterwards to pump cement grout through these holes 9 in order to fill the open space between the wall of the borehole in stratum 4 and casing 7. But the current of the water prevents the hardening of the cement and water flows down uninterrupted, driving the oil in stratum 5 away from the borehole. 10 shows the surface of the water in the borehole. Arrows 15 and 16 indicate the flow of water from one stratum to another.

Fig. 2 is a schematic vertical section of the same borehole, showing how the cementing process is proposed to be done according to the present invention. Through the holes 9 it is proposed to pump a mud-laden fluid filling the open space between the wall of the ground and casing 7 and also the space between casings 7 and 8. The borehole should also be filled with mud-laden fluid. In both cases the surface of the mud-laden fluid is indicated by 11.

Due to the hydrostatic pressure of the mud-laden fluid on the wall of the borehole and the slowness with which the water from this mud-laden fluid percolates into the wall of the borehole, all of the respective layers of the ground are being sealed off and now no circulation of fluids from one stratum to another is possible. After this has been done, it is proposed to pump cement grout through these holes 9, which ce-

ment partially displaces the mud-laden fluid between the casing 7 and the wall of the borehole. Now no circulation of fluids disturbs the cement at the time of its hardening, and the cement becomes a hard mass.

Furthermore it could happen that when cement grout is displacing the mud-laden fluid between casing 7 and the wall of the borehole at the stratum 4, this cement grout 10 sinks down below stratum 4, thereby not causing a strong watertight joint between casing 7 and stratum 4. To prevent such a calamity it is proposed first to fill the space between casing 7 and the wall of the borehole and the space inside casing 7 with mud-laden fluid as the surface 11 indicates, and afterwards to pump a plastic substance through holes 9 between casings 8 and 7 and the wall of the borehole thereby partially dis- 15 place the mud-laden fluid and afterwards to pump cement grout into this plastic substance, thereby driving part of this plastic substance below holes 9, thus preventing the cement grout from sinking down below 20 stratum 4. The cement grout will now harden thus making a strong tight joint between the casings 8 and 7 and the wall of the borehole at stratum 4.

Fig. 3 is a schematic vertical section of 30 the same borehole after all the mud-laden fluid inside casing 8 has been taken away and exploitation of oil from stratum 5 has begun.

The arrows 17 indicate the flow of the oil 35 from stratum 5 into the borehole with 14 in-

dicating the surface of the oil standing in the borehole.

What I claim as new and desire to secure by Letters Patent of the United States is:—

1. Process of sealing off fluids occurring 40 in boreholes for oil-wells, consisting in filling the spaces between the wall of the bore-hole and between casings inserted therein with a mud-laden fluid, causing through holes in the casings a hardening substance 45 to partially displace the said mud-laden fluid and to contact any impervious stratum near the oil-stratum and the casings inserted therein and allowing the hardening substance to harden.

2. Process of sealing off fluids occurring 50 in boreholes for oil-wells consisting in filling the spaces between the wall of the borehole and between casings inserted therein with a mud-laden fluid, causing through holes in 55 the casings a more plastic substance to partially displace the said mud-laden fluid and to contact any impervious stratum near the oil stratum, causing in a similar manner a hardening substance to partially displace 60 said plastic substance and to contact said impervious stratum and the said casings inserted therein, and allowing the hardening substance to harden.

In testimony whereof I affix my signature 65 in presence of two witnesses.

CARL HENRIK LIEDBECK.
